UNITED STATES PATENT OFFICE.

BRUNO O. REICHARDT, OF NEW YORK, N. Y.

BUNG-LOCK.

1,071,796.

Specification of Letters Patent.

Patented Sept. 2, 1913.

Application filed December 17, 1912. Serial No. 737,349.

To all whom it may concern:

Be it known that I, BRUNO O. REICHARDT, a subject of the Emperor of Germany, residing at New York, in the county of New York and State of New York, have invented 5 certain new and useful Improvements in Bung-Locks, of which the following is a specification.

This invention comprehends certain new 10 and useful improvements in bungs and relates more particularly to means whereby a bung may be locked into a barrel to prevent an unauthorized person removing the same.

15 The primary object of the invention resides in the provision of a bung of this nature which shall be of extremely simple construction, cheap to manufacture, and which may be unlocked only by the use of a key.

20 A further and more specific object of the invention is to provide a barrel bung having a spring-pressed pawl adapted for engagement with teeth formed on the bushing, said pawl being movable by a key inserted 25 into the bung.

There is a great need for some means whereby barrels containing wine, liquor, oil, 30 gasolene, or the like, may be securely closed and locked so as to prevent their contents being wasted or stolen. My improved bung 35 is designed to answer this purpose.

With these and other objects in view, as will become more apparent as the description proceeds, the invention consists in certain 40 novel features of construction, combination, and arrangement of parts, as will be hereinafter fully described and claimed.

For a complete understanding of the invention, reference is to be had to the following 45 description and accompanying drawings, in which,

Figure 1 is a top plan view of my improved barrel bung, Fig. 2 is a transverse sectional view through the bung and bushing 50 therefore, and, Fig. 3 is a longitudinal sectional view of my invention.

Referring in detail to the drawings by numerals, 1 designates a portion of a container such as a cask, tank, or barrel, provided 55 with a circular opening in which is positioned a casing or bushing 2. The bushing comprises an essentially cylindrical body portion, having its interior diameter reduced and threaded, as at 3, whereby a shoulder 4 is formed. The inner end of the reduced portion 3 is further reduced in diameter by

the downwardly and inwardly inclined wall 5 and terminates in a vertical wall 6. The bushing 2 is formed intermediate its ends, with the annular flange 7, which is apertured to receive the fastening members 8, which secure the flange to the container 1. A rubber gasket 9 is interposed between the interior of the container 1 and the flange 7 to provide an air-tight joint. If desired, the exterior of the bushing may be reduced at its inner end, as shown at 10.

A cylindrical bung 11 having a reduced threaded intermediate portion 12 and a further reduced inner end portion 13, is positioned for longitudinal and rotational movement within the bushing 2. The exterior of the bung conforms in all essential respects to the interior of the bushing and therefore when said bung is screwed tightly into position, a close joint is formed around its inner end walls, and the shoulder 14 formed by the reduced portion 12 bears tightly against a rubber gasket 15, thereby producing an air-tight joint. The outer end of the bung is formed with the flange 16 for engagement with the outer edge of the bushing 2 and is further provided with the wrench openings 17 to receive a tool, by means of which the bung may be either 75 screwed into or out of the bushing.

My improved locking means includes a pawl 18 mounted intermediate its ends upon the pivot rod 19, which rod extends across a recess 20 formed in one side of the bung 90 head 11. The recess is enlarged at one end to provide room for a key, which will be described later. A flat metal spring 21 is fixed at one end to the end wall of the recess 20 and bears at its other end against the pawl 18, thereby holding the same normally in engagement with the teeth 22, formed upon the interior of the bushing 2 adjacent its outer end. It will be noted upon reference to Fig. 3, that the teeth 22 extend from the shoulder 23 to the outer end of the bung and that the tooth engaging end of the pawl 18 is normally projected out of the recess 20 into engagement with one of these teeth. Collars 24 positioned upon the pivot rod 19 hold the pawl 18 away from engagement with the top and bottom walls of the recess 20. When the bung is at the extremity of its inward movement, the pawl 18 engages the teeth 22 near their inner ends, but it will be 110 seen that since these teeth are of an extreme length, it is possible to lock the bung no

matter how far it is screwed into the bushing 2. To provide for disengaging the pawl 18 from the teeth 22, I provide the keyhole 25 opening upon the outer face of the bung 5 and communicating with the recess 20, and the circular portion of the keyhole extends somewhat below the bottom wall of the recess, as indicated at 26. To release the pawl from locking engagement, a suitable key 27 10 is placed in the keyhole and rotated so as to engage the pawl and rotate it against the pressure of the spring 21. When this has been done, a wrench may be inserted in the openings 17 and the bung rotated, either inwardly or outwardly.

It is to be understood that while I have shown and described the preferred embodiment of my invention, I do not wish to be limited to this exact construction, and arrangement of parts. If desired, I may apply my improved locking means to bungs of various constructions, which bungs may be, if desired, equipped with suitable faucets or spigots.

Having thus described my invention, what I claim is:—

1. The combination with a container having an opening formed therein, of a cylindrical bushing positioned within said opening, the interior of the bushing being threaded for a portion of its length adjacent its inner end and provided adjacent its outer end with a plurality of longitudinal teeth, a threaded bung positioned within said bushing and provided intermediate its ends with

a recess, a pawl pivoted intermediate its ends within said recess and adapted for engagement at one end with said teeth, means for holding said pawl normally against the teeth, the bung being formed with a keyhole, 40 and a key adapted to be rotated within said keyhole for the purpose of disengaging the pawl from the teeth.

2. The combination with a container having an opening formed therein, of a bushing positioned within said opening, the bushing being internally threaded for a portion of its length and provided adjacent its outer end on its interior wall with a plurality of longitudinal teeth, a threaded bung positioned within said bushing and formed intermediate its ends with a recess, 45 said recess opening upon the periphery of the bung, a pawl pivoted intermediate its ends within said recess, a flat metal spring secured at one end to the inner wall of the recess and bearing at its other end against said pawl whereby the latter is held in engagement with the teeth, the bung being formed with 50 in a keyhole, a key being adapted to be rotated within said keyhole to disengage the pawl from said teeth, and means whereby the bung may be rotated.

In testimony whereof I affix my signature in presence of two witnesses.

BRUNO O. REICHARDT.
